PLAYGROUND APPARATUS

Robert E. Martens, Charleston, W. Va.

Application March 7, 1955, Serial No. 34,872

Term of patent 14 years

(Cl. D34—5)

Fig. 1.

Fig. 2.

Fig. 3.

Figure 1 is a side elevation of a playground apparatus showing my new design as viewed from the right of Figure 3;

Figure 2 is a top plan view of the playground apparatus showing my new design; and

Figure 3 is an end elevation thereof viewed from the left of Figure 2.

I claim:

The ornamental design for a playground apparatus, as shown.
